UNITED STATES PATENT OFFICE.

CHARLES POLAKOFF AND RUDOLF LANGE, OF BUFFALO, NEW YORK.

COMBINATION FURNITURE.

SPECIFICATION forming part of Letters Patent No. 449,430, dated March 31, 1891.

Application filed January 2, 1891. Serial No. 376,446. (No model.)

To all whom it may concern:

Be it known that we, CHARLES POLAKOFF and RUDOLF LANGE, of Buffalo, in the county of Erie and State of New York, have jointly 5 invented certain new and useful Improvements on a Combined Wash-Stand, Writing-Desk, Bureau, and Safe; and we do hereby declare that the following description of our said invention, taken in connection with the 10 accompanying sheets of drawings, forms a full, clear, and exact specification, which will enable others skilled in the art to which it app- 15 pertains to make and use the same.

This invention has general reference to improvements in a combined wash-stand, writing-desk, bureau, and safe; and it consists, essentially, in the novel and peculiar combination of parts and details of construction, as hereinafter first fully set forth and described, 20 and then pointed out in the claims.

In the drawings already referred to, which serve to illustrate our said invention more fully, Figure 1 is a front elevation of our improved writing-desk, wash-stand, bureau, and 25 safe combined, the cover of the wash-stand (being also the top of the writing-desk) being shown as open. Fig. 2 is a front elevation of the combined furniture, showing the same as it appears as a writing-desk. Fig. 3 is a 30 side elevation of the same. Fig. 4 is a longitudinal sectional elevation of the lower portion of the furniture in line *x x* of Fig. 6. Fig. 5 is a similar view on an enlarged scale, the spring-casing for the water-supply pipe 35 being also shown in section. Fig. 6 is a trans- 40 verse sectional elevation in line *y y* of Fig. 2. Figs. 7, 8, and 9 are detail views of the desk-hinges and the desk-top, respectively. Fig. 45 10 is an elevation in section of the spring-casing detached. Fig. 11 is a section of a fragment of the base and the covers, showing the catch to lock the covers to the base.

Like parts are designated by corresponding letters of reference in all the figures.

The object of this invention is the production of an efficient and serviceable combination furniture, consisting of a wash-stand, writing-desk, bureau, and safe for safe keeping of valuable papers, jewelry, &c., as generally found in households. To attain this object we construct this combination furniture substantially of a rectangular base A,

consisting of side pieces A', base-piece A'', and back A'''. Within this base are horizontal partitions *a* and a vertical partition *a'* 55 to divide the interior of the base into a number of compartments *a''* to receive drawers B B', B' being a blind drawer, and a further compartment *a'''* to contain a water-receptacle C, as shown in Fig. 4, and to which access is had through the hinged door B''.

At a suitable distance below the top edge of the base A there is a horizontal partition *b*, wherein is a suitable hole *b'*, below which and attached to the under side of the horizontal partition *b* there is affixed a wash-basin D, connected with the waste-water receptacle D by a pipe D'. This horizontal partition *b* may be a marble slab, if desired, so as to be readily cleaned and prevent water 65 from soaking into said partition. Upon this horizontal partition *b* is placed a water-supply pipe E, supported on its closed end by a standard *e* and near its other end by a casing F, which casing contains a spiral spring F', 70 secured with one end to the casing and with the other end to a stuffing-box E', having a follower *e'* and packing *e''*, by means of which a continuation E'' of said supply-pipe E makes a water-tight connection with said supply-pipe E, said continuation E'' leading to a reservoir G, located on the top of the base A, as hereinafter to be referred to. From the supply-pipe E leads a faucet-pipe H upwardly, which pipe H is supplied with a faucet H', 75 by means of which water may be allowed to run to the basin D of the supply shut-off whenever desired.

Upon the base A is located a top structure I, which in the main consists of the water-reservoir G, surrounded by frame-work to form pigeon-holes I', and a compartment I'', within which is located a small fire-proof safe or strong box J, Fig. 2, to receive jewelry, papers, and other valuable articles for safe 90 keeping, said water-reservoir G continuing above the top structure I, as shown in Figs. 2 and 3, and having in its face a looking-glass G' to serve as an ornamental as well as useful appendage to the furniture. The top 95 structure I has in front two doors K K' to close the pigeon-holes and the strong box in the usual way and protect them from dust, &c.

To the lower edge of the top structure I is

hinged a top leaf L, to which in turn is hinged a second leaf L', the two leaves, when folded down, forming a cover for the base A, while when the leaf L' is folded forward, as shown 5 in Fig. 3, it forms, in conjunction with the top leaf L, the top of a writing-desk, the two leaves L L' being hinged together at their edges by means of stop-hinges M, of the usual construction, so as to support the leaf L' in 10 its extended condition, as shown in Fig. 7, while the leaf L is hinged to the cross-piece J' of the top structure, Fig. 6, by hinges M', Fig. 7.

The whole structure heretofore described 15 may be manufactured in wood and metal in any approved design and ornamentation at the option of the manufacturer, and can be made in various woods, so as to satisfy the requirements of the trade.

20 In their normal position the top leaves L L' are located upon the projecting portion of the base A to cover the depression N, within which the faucet-pipe and the faucet, and also the supply-pipe and the spring-casing, 25 are located. If the furniture is to be used as a writing-desk, the leaf L' is lifted and folded forward, so that the two top leaves L L' serve as the top of a desk, while if the device is to be used as a wash-stand the two leaves L L' 30 are lifted up and swung against the top structure I. Now the faucet-pipe H will swing upward, turning in its standard e and in the case F by the action of the spiral spring F' in said case, which spiral spring, being 35 properly tensioned and affixed with one end to the casing F and with the other end to the stuffing-box E', causes the pipe E to partly revolve and the faucet-pipe H to bear against the top leaf L' and to keep the two leaves L 40 L' in an upright position, a suitable catch O in the base A engaging the leaf L and holding the leaves L L' in their normal position, as shown in Fig. 11, and also keeping the faucet-pipe H in a depressed condition where said 45 pipe H occupies space in the wash-basin D, as shown in dotted lines in Fig. 6.

It will be observed that the water-supply pipe from the reservoir G leads the water-supply through the pipe E to the faucet H', 50 and from the wash-basin through the pipe D' to the waste-water receptacle C, which latter is preferably to be made large enough to receive the entire contents of the water-reservoir, so that an overflow thereof cannot take 55 place.

If desired, the supply-pipe may be connected with a city water-supply and the waste-pipe

connected with any system of sewerage, thereby making the combined furniture a permanent household fixture. We prefer it, however, in its portable form, in which it will be found most serviceable, especially so in crowded cities, where living-rooms are high in price and where space must be utilized to the greatest extent. 65

The drawers B B may be used for storing clothing and other household paraphernalia, thus performing the functions of a bureau in an efficient manner.

Having thus fully described our invention, 70 we claim as new and desire to secure to us by Letters Patent of the United States—

1. The improved combined wash-stand, bureau, writing-desk, and safe hereinbefore described, consisting, essentially, of the base 75 having a waste-water receptacle and a partition, to which is affixed a wash-basin, a journaled water-supply pipe having a stuffing-box and a faucet-pipe and faucet, a spring mechanism on said supply-pipe to keep the faucet-pipe in an erect position, hinged leaves to cover the depression in the base containing the water-supply pipe, a catch to retain the leaves and faucet-pipe in a depressed position, and a water-reservoir in the top portion of the 80 furniture and connected with the supply-pipe, as and for the object stated.

2. In a combined wash-stand and writing-desk, a journaled supply-pipe having a standard on one end and a spring-casing on the 85 other end, a spiral spring within said casing attached with one end to the casing and with the other end to the supply-pipe, and a cover and catch, as described, to hold the faucet-pipe and faucet in a depressed position, as 90 and for the object stated.

3. In a combined wash-stand and writing-desk, the combination, with the base having the waste-water receptacle, a water-supply, and a wash-basin, of two covers hinged one 100 to the other, as described, the top structure having the water-reservoir and a depression therein supplied with a strong box, and the doors on the top structure, as and for the object set forth. 105

In testimony that we claim the foregoing as our invention we have hereto set our hands in the presence of two subscribing witnesses.

CHARLES POLAKOFF.
RUDOLF LANGE.
